(57) **CLAIM**

The ornamental design for a stiletto shoe shaped tape dispenser, as shown and described.

DESCRIPTION

FIG. 1 is a perspective view of a stiletto shoe shaped tape dispenser showing the new design;

FIG. 2 is a side elevational view thereof;

FIG. 3 is another side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken line showing of a roll of tape and means for cutting the tape are included for the purpose of illustrating environmental structure and form no part of the claimed design.
